UNITED STATES PATENT OFFICE.

CHARLES H. GAGE, OF PHILADELPHIA, PENNSYLVANIA, ASSIGNOR TO CHARLES W. YOUNG & CO., OF PHILADELPHIA, PENNSYLVANIA, A FIRM COMPOSED OF GEORGE F. YOUNG AND D. WILSON B. YOUNG.

DESIGN FOR A SOAP DISPENSER.

Application filed May 19, 1928. Serial No. 26,763. Term of patent 14 years.

To all whom it may concern:

Be it known that I, CHARLES H. GAGE, a citizen of the United States, residing at Philadelphia, in the county of Philadelphia and State of Pennsylvania, have invented a new, original, and ornamental Design for Soap Dispenser, of which the following is a specification, reference being had to the accompanying drawing, forming part thereof.

Fig. 1 is a view in side elevation of a soap dispenser showing my new design.

Fig. 2, is a view in front elevation of Fig. 1; and

Fig. 3, is a top or plan view of Fig. 1.

I claim:

The ornamental design for a soap dispenser, as shown.

CHAS. H. GAGE.
